COKE OVEN CONSTRUCTION

Maurice D. Curran, Glendale, Mo., assignor to
 Tar & Petroleum Process Company, Chicago,
 Ill., a corporation of Illinois

Application August 8, 1936, Serial No. 94,918

5 Claims. (Cl. 202—102)

The present invention relates to improvements in coke oven construction.

The patent to Knowles No. 1,745,996, granted February 4, 1930, discloses a sole-fired coke oven heated by a plurality of independent sole combustion flues arranged beneath the sole of the oven. Said patent discloses an improvement in means for distributing the air and waste heat gases in the flues to provide increased heating in the flues toward the middle of the oven and to decrease excessive heating at the ends of the oven, thereby improving uniformity of heating throughout the lengths of the flues. The present invention relates to the same general subject matter as the Knowles patent referred to, but contemplates other means for accomplishing the uniformity of flue heating. Certain subject matter disclosed but not claimed herein are claimed in applicant's applications Serial Nos. 94,916 and 94,917, both filed August 8, 1936.

An object of the present invention is to provide a coke oven having a horizontal floor with heating flues therebeneath, together with relatively simple means for accomplishing uniform heating effects throughout the lengths of said flues.

A further object is to provide a coke oven construction of the kind referred to which will accomplish uniform heat distribution in the flues with a minimum of obstructions in said flues.

Further objects will appear as the description proceeds.

The one figure of the drawing is a vertical cross sectional view taken longitudinally of a coke oven embodying the principles of the present invention.

The numeral 1 indicates the floor or sole of a coke oven, and the numeral 2 indicates the roof thereof. Said roof is provided with the openings 3—3 for charging coal into the oven, and the numeral 4 indicates a standpipe through which by-products may be taken off. Each front of the oven chamber is provided with a door, said doors being indicated by the numerals 5 and 6.

Disposed below the floor 1 are a plurality of flues 7 extending longitudinally of the oven. Said flues may be separated by walls (not illustrated) upstanding from the horizontal wall 8, which wall defines the bottom boundary of the flues 7. As illustrated in the drawing, said wall 8 is formed to provide apertures 9—9 adjacent to the end walls of the oven whereby to provide communication from the flues 7 to the space below the wall 8. Projecting downwardly from the wall 8 is the medial wall 10 dividing the space below the horizontal wall 8 into two regenerators. Projecting from each end wall of the oven is a baffle wall 11, which baffle walls are shaped to provide apertures 12—12 adjacent to the medial wall 10. Each of said baffle walls 11—11 therefore provides

a U-shaped passageway, or hairpin passageway, indicated by the numeral 13 from a region adjacent to an end wall of the oven to a region adjacent to the medial wall 10 back to the region of the corresponding aperture 9.

Connecting with the passageways 13—13 of the regenerators at the two ends of the oven are downtakes 14—14 leading to the waste gas tunnels 15—15.

According to the illustrated embodiment of the present invention, the oven is provided with a plurality of passageways 16—16, extending from the two ends of the oven to the region adjacent to the medial wall 10. Said passageways communicate with the atmosphere at the two ends 15 of the oven, and at the middle of the oven communicate with air downtakes 17—17 which lead to the hot air tunnel 18. Said tunnel 18 communicates through the pipe 19 with the fan box 20. Said fan box 20 is connected by means of 20 pipes 21—21 (controlled by valves 21a—21a) to air manifolds 22—22 at the two ends of the oven, which manifolds 22—22 are connected by means of air inlets 23—23 to the passageways 13—13 of the regenerators at the two ends of the oven. It will be understood, of course, that the air passageways 16—16 will be protected from direct communication with the gas downtakes 14—14. Inasmuch as the details of the construction relative to the passageways 16—16 form no part of 30 the present invention, no discussion of said details is necessary herein. Such details form the subject matter of another application filed by the present applicant of even date herewith bearing Serial No. 94,917. The numerals 24—24 35 indicate gas manifolds which through gas inlets 25—25 deliver combustible gas to the flues 7—7 underlying the sole or floor 1.

Proceeding now to a description of the invention claimed herein, a baffle wall 26 is mounted in each 40 passageway 13—13, which baffle walls extend from the medial wall 10 toward the ends of the oven. Said baffle walls 26—26 are disposed in parallel relationship with the horizontal wall 8 and are located between said horizontal wall 8 45 and the baffle walls 11—11. Said baffle walls 26—26 are shaped to provide apertures 27—27 adjacent to the two end walls of the oven. In other words, said apertures 27—27 are located adjacent to the apertures 9—9 at the two ends 50 of the horizontal wall 8. The horizontal wall 8, which forms the lower boundary of the flues 7—7, is provided with a plurality of apertures 28—28 providing communication between the space above the baffle walls 26—26 and said flues 55 7—7.

The mode of operation of the above described embodiment of the present invention is substantially as follows: Gas for heating the flues 7—7 will be alternately supplied through the gas inlets 60

25—25 at the two ends of the oven. When gas is supplied through the left-hand gas inlets 25 as the parts are viewed in the drawing, air will be supplied through the inlets 23 at the same 5 end of the oven, which air, in passing through the corresponding regenerative passageway 13, will be preheated for mixture with the gas being delivered from said gas inlets 25—25. At this time products of combustion from the flues 1—7 10 will pass through the right-hand regenerative passageway 13, heating up the structure defining said passageway and passing out through the waste heat tunnel 15 at the right-hand end of the oven.

15 Continuing with the example in which gas for combustion purposes is admitted at the left-hand end of the oven, the air for combustion purposes, after passing through the corresponding regenerative passageway 13, will in considerable 20 proportions pass through the aperture 9 at the left-hand end of the oven for uniting with the gas from the gas inlets 25 at the left-hand end of the oven. However, a material proportion of the gas from the left-hand regenerative passageway 13 25 will pass along above the partition wall 26 to the apertures 28—28 to unite with unburned portions of the gas delivered toward the midregion of the oven. The result is a relatively uniform heat distribution throughout the length of the 30 flues 1—7. At the same time the products of combustion will in part pass downwardly through the apertures 28—28 at the right end of the oven and the remainder of said waste heat gases will pass downwardly through the apertures 9 at the 35 right-hand end of the oven. The result is the avoidance of excessive heat at the outer end of said flues 1—7.

Slide bricks 29—29 have been illustrated for 40 modifying the extent of the apertures 9—9. Other slide bricks 30—30 may be provided for modifying the extent of opening of the apertures 28—28.

45 Though a preferred embodiment of the present invention has been described in detail, many modifications will occur to those skilled in the art. It is intended to cover all such modifications that fall within the scope of the appended claims.

What is claimed is—

50 1. In a coke oven, in combination, a horizontal coking floor, a horizontal wall below said floor forming the lower boundary of heating flues extending longitudinally of said oven, means dividing the space below said horizontal floor into a 55 pair of regenerative chambers, means in each of said chambers providing a tortuous passageway therethrough, said horizontal floor having a plurality of apertures spaced lengthwise of said oven and providing communication between said 60 flues and said regenerative chambers, means for admitting gas to said flues at the ends of said oven remote from said dividing means, means for admitting air to said regenerative chambers, and imperforate baffle means in part defining said 65 tortuous passageways and extending from said dividing means toward the ends of said oven for distributing air through said apertures.

2. In a coke oven, in combination, a horizontal coking floor, a horizontal wall below said floor 70 forming the lower boundary of heating flues extending longitudinally of said oven, means dividing the space below said horizontal floor into a

pair of regenerative chambers, means in each of said chambers providing a tortuous passageway therethrough, said horizontal floor having a plurality of apertures spaced lengthwise of said oven and providing communication between said 5 flues and said regenerative chambers, means for admitting gas to said flues at the ends of said oven remote from said dividing means, means for admitting air to said regenerative chambers, imperforate baffle means in part defining said tortuous passageways and extending from said dividing means toward the ends of said oven for distributing air through said apertures, and means for modifying the extent of opening of said apertures. 15

3. In an oven structure, in combination, a coking floor, flues disposed below said floor, said flues being defined on their bottom sides by a wall having perforations therealong communicating with said flues, said oven structure being provided 20 with a pair of regenerative chambers disposed below said wall, dividing means disposed transversely of said oven structure medially thereof to separate said regenerative chambers, means for delivering gas to said flues at the two ends of said 25 oven structure remote from said dividing means, each of said regenerative chambers having an outlet to deliver regenerated air for mixture with gas from its corresponding gas delivering means, and imperforate baffle means extending from 30 said dividing means toward the ends of said oven structure and defining in part said regenerative chambers, said baffle means being disposed in position to retard the flow of air from said regenerative chambers through said spaced openings in said wall whereby to distribute regenerated air lengthwise of the path of flame propagation from said gas delivering means. 35

4. In a coke oven, in combination, a coking floor, said oven having longitudinal flues below 40 said floor, the lower boundary of said flues being defined by a horizontal wall having apertures spaced therealong, a medial wall dividing the space below said horizontal wall into two regenerative chambers, said apertures providing 45 communication between said regenerative chambers and said flues at regions spaced longitudinally of said oven, means for delivering gas at the two ends of said flues remote from said medial wall, and imperforate baffle walls extending from 50 said medial wall for controlling the distribution of regenerated air to said apertures in said horizontal wall.

5. In a sole-fired coke oven provided with a plurality of sole combustion flues arranged under 55 the sole of the oven for heating it, a plurality of regenerators for alternately supplying preheated air to said flues, said oven having a wall separating said regenerators from said flues, said wall being provided with spaced openings disposed 60 along said oven providing communication between said regenerators and said flues at regions spaced longitudinally of said flues, in combination, baffle walls extending from the midregion of said oven toward the ends thereof in part defining said regenerators to control the distribution of heated air from a selectable one of said regenerators to said flues and to control the discharge of waste heat gases from said flues to the other of said regenerators. 70
